UNITED STATES PATENT OFFICE.

KARL F. NYSTRÖM, OF CHICAGO, ILLINOIS.

CAR CORNER POST.

Application filed February 2, 1923. Serial No. 616,486.

To all whom it may concern:

Be it known that I, KARL F. NYSTRÖM, a subject of the King of Great Britain, and a resident of Chicago, in the county of Cook and State of Illinois, have invented a certain new and useful Improvement in a Car Corner Post, of which the following is a description, reference being had to the accompanying drawing, which forms a part 10 of my specification.

My invention relates more especially to corner posts for refrigerator cars, whereby the outer sides and end planks are reinforced at the corners of the car and the outer 15 planks and inner corner structural members firmly secured together; the invention having for its object the provision of a corner post which will not only provide a stiff, rigid construction, but which will also permit a portion or one member of the composite corner post to be readily removed when occasion requires and enable either the side or end planks to be easily removed for repair or replacement.

25 My invention contemplates a corner post composed of a number of metallic plates adapted to extend throughout the height of the car-body, with one of the plates adapted to be secured adjacent to the ends of the 30 side planks; a second plate adapted to be secured adjacent to the ends of the end wall planks, namely adjacent to the juncture of the side and end walls, that is at the corner of the car body; with a third plate adapted 35 to be secured to the adjacent longitudinal edges of the side wall and end wall plates, namely at the immediate corner of the car and therefore transversely of or across the ends of the side and end wall planks.

40 The purpose of my invention is to so arrange the respective plates and removably secure them together, that upon removing the third or intermediate plate, the ends of the side wall planks or end wall planks 45 will be uncovered and removal of any of the planks without complete dismantling of the walls made possible by sliding the desired plank or planks through the space intermediate of the adjacent longitudinal edges 50 of the other plates.

The objects and advantages of my invention will be more fully comprehended from

the detailed description of the accompanying drawings, wherein:

Figure 1 is a perspective view of a corner 55 of a refrigerator car body, with the upper portion broken away and shown in section.

Figure 2 is a cross-sectional view of a corner of a refrigerator car body, disclosing my improved corner post.

In the particular exemplification of the invention, I disclose a portion of one corner of a refrigerator car body wherein the outer side wall and end planks 5 are disposed lengthwise of the sides and ends of the car 65 and secured to the posts 6 of the car frame or structure to which the inner wall sheathing 7 is also secured.

The walls of the car, namely the space intermediate of the outer and inner wall elements is shown provided with layers of suitable insulating material indicated at 8 and insulation paper 9 at the inner surface of side and end planks 5 and also between the insulating material 8 and the inner sheathing 75 7.

As this part of the construction may be of any suitable type and material and forms no part of my invention, a further detailed description thereof need not be entered into.

80 The outer corner post and reinforcing element consists of a pair of substantially identical metallic members or plates 10, 10; one of which is secured adjacent to the ends of the side wall planks 5, while the other plate is secured adjacent to the ends of the 85 end wall planks 5.

The longitudinal edges of both plates 10, 10, at the ends of the side wall planks and the end wall planks, respectively, are bent 90 or flanged outwardly, preferably at right angles to the main portion of the plates, as shown at 11. The angle members or plates 10, 10 are firmly secured preferably by means of rivets 12 to the car framing; at 95 the bottom to the side and end sills 13, 13 and at the top in a similar manner to the side and end plates (not shown in the drawings). The side and end planks 5, 5, as well as the posts 6 are held in place preferably 100 by means of bolts 14, which are disposed through the corner-post members 10.

With the post members or plates 10, 10 arranged as shown and described, it is ap-

parent that the ends of the wall planks 5 at the immediate corner of the car are exposed, as they extend substantially flush with the flanged edge of the respective post 5 member or plate 10.

The immediate corner of the car wall, namely the space intermediate of the adjacent flanged edges of the two plates 10, 10, is provided with a cover member or metallic plate 15, preferably somewhat in the nature of a channel, which has one longitudinal edge bent or flanged outwardly as shown at 16 to extend parallel and flush with the flange 11 of the side wall plate 10, while 10 the other longitudinal edge 17 is bent or flanged outwardly to extend parallel and flush with the flange 11 of the end wall plate 10.

The intermediate portion of the corner 20 member 15 is preferably disposed tangentially to or across the end wall and side wall planks 5, namely at an obtuse angle to the flanges 16 and 17 thereof; and this intermediate portion of the cover sheet or 25 plate 15 is therefore of width sufficient to extend across the angle or space left by the non-meeting outer surfaces of the side wall planks 5 and the end wall planks 5. The flanges 16 and 17 of the cover member or 30 plate 15 are preferably removably secured to the flanges 11 of the side wall and end wall plates 10, respectively, by means of suitable bolts and nuts as shown at 18 or rivets if desired; the flanges 11 of plates 35 10 and the flanges 16 and 17 of plate 15 being provided with registering holes, in order that the cover plate may be easily put into place and removed.

The ends of each side and end wall plank 40 are preferably bolted or secured to the respective members or plates 10 as shown, thereby securely fastening the ends of the planks.

In the event that either a side wall plank 45 or an end wall plank is to be removed and replaced, it may be readily accomplished by simply removing the intermediate corner-post member or cover plate 15 after removing the bolts and nuts 18 or rivets, as the 50 case may be, thereby freeing the ends of the planks and permitting them to be slid through the opening intermediate of angle post plates 10, namely through the space or opening covered by the post member or 55 plate 15 after the respective bolts 14 and other fastening means at various points in the planks have been removed.

It is also apparent that the flanges of the 60 respective plates, aside from providing a convenient manner of securing the plates together, also constitute reenforcing ribs for the corner-post and therefore provide a very rigid structure which can be easily applied and also readily removed when occasion requires.

The construction shown I believe to be the simplest embodiment of my invention, which has been described in terms employed merely as terms of description and not as terms of limitation as structural modifications are 70 possible and may be made without, however, departing from the spirit of my invention.

What I claim is:-

1. In a car having outer side and end wall planks, a corner post comprising a vertically disposed plate adapted to be secured to the side wall planks adjacent to the ends thereof, with one longitudinal edge of the plate being bent outwardly, a second plate secured to the end wall planks adjacent to the ends thereof, one longitudinal edge of the plate being bent outwardly, the bent longitudinal edges of said plates being in spaced relation, and a third plate of width substantially equal to the spacing between the first two mentioned plates, the longitudinal edges of the third plate being bent to extend flush with the bent edges of the first two mentioned plates and being removably secured thereto. 75 80 85 90

2. A corner post of the character described adapted to lap about the side and end wall planks of a car body, comprising a plurality of plates having outwardly disposed longitudinal edges, one of said plates being secured to the outer side walls of the car, while the other plate is secured to the outer end walls of the car, with the adjacent longitudinal edges of the two plates arranged in spaced relation, and a channel plate arranged intermediate of the two plates with the longitudinal sides of the channel plate removably secured to the outwardly disposed edges of the first two mentioned plates. 95 100 105

3. In a car body provided with side and end wall planks disposed lengthwise of the sides and ends of the car body in superposed relation, corner posts composed of three metallic plates disposed from top to bottom of the car body, with one plate secured to the side wall frame structure of the car inlapping relation with the outer surfaces of the side wall planks and having an outwardly disposed longitudinal edge, the second plate being secured to the end wall frame structure of the car inlapping relation with the outer surfaces of the end wall planks and having an outwardly disposed longitudinal edge, the two plates being spaced from each other, while the third plate has both longitudinal edges disposed outwardly and is disposed diagonally to the sides and ends of the car, intermediate of the first two mentioned plates with its longitudinal edges secured thereto. 110 115 120 125

4. A corner post of the character described adapted to lap the adjacent edges of the side and end walls of a car, composed of a plurality of plates, one of said plates being se- 130

cured to the side wall of the car and provided with an outwardly disposed portion at one longitudinal edge, a second plate being secured to the end wall of the car and 5 provided with an outwardly disposed portion at one longitudinal edge, the two plates being in spaced relation with each other, and a third plate arranged intermediate of the first two mentioned plates and having portions 10 on both longitudinal edges thereof adapted to extend flush with the outwardly disposed portions of the other two plates and be removably secured thereto.

5. In a railway car having side wall planks 15 and end wall planks disposed, respectively, longitudinally and transversely of the car, an outer corner post composed of a vertically arranged angle plate secured adjacent to the ends of the superposed side wall planks with 20 one longitudinal side of the plate disposed outwardly, a second vertically arranged angle plate secured adjacent to the ends of

the superposed end wall planks with one longitudinal side thereof disposed outwardly, the outwardly disposed longitudinal sides of the two plates being spaced apart so as to permit passage of either the side wall planks or the end wall planks lengthwise therebetween, both plates being removably secured, respectively to the side wall planks 25 and the end wall planks, and a third plate having an intermediate portion of width substantially equal to the spacing between the longitudinal sides of the first two mentioned plates and outwardly bent longitudinal edges adapted to extend flush with the outwardly disposed sides of the first two mentioned plates and be removably secured thereto. 30 35
